PACKING AND SHIPPING DEVICE

Sydney R. Koons, Cleveland, Ohio

Application February 12, 1931. Serial No. 515,225

3 Claims. (Cl. 229—87)

The present invention relates to an improvement in packing and shipping devices, especially foldable packets or wrappers for shipping articles of irregular shape and contour having smoothly-finished surfaces or polished portions which must be thoroughly protected and safeguarded during handling and shipment thereof. For example, the present device or packet is particularly useful for shipping engine valves of the poppet type having beveled seating surfaces and cylindrical stems which have been accurately machined and ground, the device or packet being designed and constructed to expedite wrapping and packing operations and to fold readily into the same general shape as the valve, with the walls of the device buttressed or braced against each other on angular lines to provide a rigid and strong receptacle or package. The device is also made to cushion or absorb jars and shocks and to permit it to be folded or wrapped closely against both the head and stem of the valve so that the valve will be confined snugly and tightly therein. When folded the device or packet also provides an angular package with flat sides which permit any number of such packages to be compactly assembled and tightly packed within wooden shipping boxes, crates or the like. In that connection be it understood that the weight and irregular shape of the valve and package must be considered in packing and transporting such goods together or in bulk, and that the present packing device has been especially constructed to reduce the hazards of injury to the valves during packing operations and when shipped together in bulk, and also to permit packing to be accomplished expeditiously at a low cost as will hereinafter be more fully explained.

In the accompanying drawings, Fig. 1 is a plan view of my improved shipping and packing device, and Fig. 2 an edge view thereof. Figs. 3 and 4 show the device folded upon and enclosing a valve, Fig. 3 being a cross section on horizontal line 3—3 of Fig. 4, and Fig. 4 being a side elevation of the same parts. Fig. 5 is a sectional view in plan on horizontal line 5—5 of Fig. 6, and Fig. 6 is a sectional view vertically through the packet and a side view of the valve enclosed therein. Figs. 7 and 8, are perspective views of the same packet and valve, unfolded and folded, including a sheet of wrapping paper which may be used therewith to bind and secure the parts together. Fig. 9 is a perspective view of a modified form of the invention made in two pieces or parts, and Fig. 10 is a sectional view of this modified form of device folded and wrapped around a valve.

Now, referring to Figs. 1 to 6, the shipping and packing device therein delineated consists of a flat piece A of cardboard of corrugated or cellular construction, having a square or rectangular base or central portion 2 bounded on its four sides by triangular or tapering border portions or wings 3, each of which includes a relatively long and narrow arm or tongue 4 extending radially in respect to base portion 2 when unfolded and lying flat in the same plane therewith. The plane surfaces or facings of piece A are thin flat sheets 5 of paper or cardboard glued to a corrugated inner core 6 of cardboard so that a pliable but relatively stiff body is provided which possesses cushioning properties. This composite piece of material is creased or scored on straight lines at definitely fixed places therein to permit the wings 3 and arms 4 to be folded into columnar form having a hollow flaring base of larger dimensions. Thus, the fold lines between the respective portions of the devices are formed in multiple by straight creases 7 at the four sides of the square base portion 2 and parallel creases 8 at the juncture of each arm 4 with its respective wing 3. An additional crease 9 may also be used with advantage in some instances, as shown in Fig. 9, depending upon whether a one-piece or a two-piece structure is desired, or in case a different form of valve head is to be enveloped by the wings 3. Appropos, it may be here stated that this invention has been especially created for a valve B made of an alloy of metal which comprises a circular head b having a beveled edge b' accurately finished or ground, and a cylindrical stem b'' which is also smoothly finished.

The foldable wing portions 3 are of equal area and have short straight connecting portions 10 where joined to the middle area or square base portion 2, while the four arms or elongated portions 4 are adapted to be folded in pairs, one pair being made of narrower width than the other so that the wider arms may be folded to overlap the straight edges of the narrower arms and bring the plane faces of the wider arms in solid abutting relation against the straight squared edges of the narrower arms, see Fig. 3. Accordingly, each flat arm 4 may be folded, pressed and fastened tightly against the valve stem b'' and buttressed against each other at corner points, and the triangular wing portions 3 may be folded into inclined bracing relations with each other at their meeting edges and relatively to such arms and the square base portion 2, see Figs. 4 and 6. Valve head b is circular, and the angle of inclination

of each wing portion 4, when folded, may be the same or approximately the same as the angle of the beveled edge b' of the head so that this circular head will be engaged and firmly held at four 5 equi-distant radial points by the four wing portions 4, see Fig. 5. On the other hand, the beveled edge b' of head b is spaced apart from the remaining enveloping areas of the inclined walls or wings 3, that is, at each corner in the triangular 10 hollow space formed by the four folded wings 3, and each wing is also spaced apart from the neck portion b''' of the valve, whereas the end of the valve head is firmly seated upon the cushioning base portion 2. Thus, when this packing and 15 shipping device is folded snugly and tightly around the valve head and its stem, and the four arms 4 are tied by cords 11 or fastened together by other means, say as delineated in Figs. 4 and 20 6, the valve is completely enveloped and cushioned by protecting walls, which though spaced apart in major areas from the valve head and stem, nevertheless prevent the valve from shifting laterally or longitudinally in the package, and with 25 complete protection to the highly-finished surfaces of the valve.

The protection to the valve afforded by the use of this package also begins with and involves the making and packing operations. Thus, when the valves are ground and completed they are taken 30 singly, by the stem, and deposited in an upright position upon the central base portion 2 of the packing device while the base portion is loosely seated above a chamber, pocket, or means spaced to admit the square base portion 2 when pressure 35 is applied downwardly upon the valve and the base portion 2 is forced into the chamber, pocket or space having the proper dimensions to receive it. This simple step folds the four wings and arms upright into parallel or substantially parallel 40 relationship with the stem, and the four arms 4 are then brought together and tied, either by hand or in a tying machine, thus completing the packing operation safely and expeditiously for each individual valve.

In lieu of tying the arms 4 together by cord, wire or equivalent means, a sheet 12 of paper may 45 be used to wrap the valve therein and to secure the arms of the device together, reference being had to Figs. 7 and 8. In this case, the paper sheet

12 is first laid upon the unfolded packing device and the valve deposited centrally thereon and upon the middle or base portion of the device as delineated in Fig. 7. Then, the wings and arms are folded upwardly around the valve, and the 50 protruding ends and parts of the paper sheet twisted around the four arms as shown in Fig. 8.

In Figs. 9 and 10 I show a packing or shipping device which is constructed and used in substantially the same way as the device shown in Figs. 1 to 6, except that the device is made of two pieces or parts A' and A'', respectively, each having square or rectangular central portions and a pair of wings and arms. These separate pieces are superposed at their middle with the arms on one piece laid at right angles to the arms on the other piece, and they may be secured together in that relation by an adhesive or other means.

What I claim is:

1. A packing or shipping device for valves, consisting of a composite piece of material including a corrugated paper sheet, comprising a rectangular area bounded by triangular areas terminating in relatively long and narrow extensions and creased parallel to permit said piece to be folded partly into pyramidal form and partly into tubular form.

2. A packing or shipping device for valves, comprising a straight-sided base portion having foldable side portions of angular shape and elongated straight portions, certain of said straight portions being of less width than other straight portions and all of said straight portions being of less width than the side portions, to provide a hollow packet of columnar form having a pyramidal base.

3. A packing or shipping device for valves, consisting of a flat piece of relatively stiff but pliable material having a pair of foldable triangular border portions and narrowed arms extending in opposite directions therefrom and including a second pair of foldable triangular border portions and narrowed arms extending at an angle to said first pair of foldable border portions and arms, said border being formed with double parallel creases to form a portion adapted to fit the valve base.
